UNITED STATES PATENT OFFICE.

JOHN A. TAGGART, OF WILMETTE, ILLINOIS.

FORM STRUCTURE FOR CONCRETE CONSTRUCTION.

Application filed April 25, 1921. Serial No. 464,238.

To all whom it may concern:

Be it known that I, JOHN A. TAGGART, a citizen of the United States, residing at Wilmette, in the county of Cook and State 5 of Illinois, have invented new and useful Improvements in Form Structures for Concrete Construction, of which the following is a full, clear, concise, and exact description, reference being had to the accompanying drawing, forming a part of this specification.

This invention relates to the construction and shape of an improved type of form structure for concrete construction, and 15 more particularly relates to the molds, forms or false work used in the construction of concrete structures.

This invention is an improvement of the form structure disclosed in my co-pending 20 application, Serial No. 331,862, filed October 20th, 1919. The improvement in the construction of the falsework used for concrete structures over my prior application, as herein disclosed, consists essentially in 25 improvements in the construction of the mold or form, especially in the soffit construction and the manner of interlocking said soffits and the various forms or molds used in the construction, so as to construct 30 a complete solid and rigid structure which utilizes the strength of the timbers and lumber used in constructing the forms for the support of the falsework.

It is one of the objects of this invention, 35 therefore, to provide an improved form or falsework construction which will transmit the weight of the form construction to the center line of the girders, and in which the timber used in constructing the falsework is 40 utilized to assist in the support of the falsework and the concrete floor construction placed thereon.

Another object of the invention resides 45 in the production of improved types of forms or sections which are so standardized that they can be readily remodeled and used for spans of different lengths and joists of different depths without sacrificing their strength, and which can be accomplished at 50 a minimum cost.

Another object resides in the production 55 of an improved form or section which is so constructed that it can be repeatedly used without showing material effects of wear or deterioration.

A further object of the invention comprises the production of an improved form of truss construction in which the connection between the tension members and the truss is self-adjusting to any angle which 60 said tension member may be required to assume for constructions of different kinds and dimensions.

An additional object consists in the production of an improved means for breaking 65 the suction between the forms and the concrete.

Other objects of the invention will be apparent from the following description, the accompanying drawings and the appended 70 claims.

A preferred embodiment of the invention is illustrated in the accompanying drawings; in which,

Fig. 1 is an end view partly in section of 75 a built-up construction showing the column and girder molds, together with the joist mold construction and its supporting truss construction;

Fig. 2 is a cross section through one of the 80 forms or molds, and illustrates the means used to break the suction between the form and the concrete, and also illustrates the soffit construction;

Fig. 3 is an illustration in cross section 85 through a plurality of molds or forms;

Fig. 4 is a side view of a mold or form, and illustrates the wedges used to interlock 90 the form sections and the soffits, whereby these elements when thus interlocked are substantially as strong as a mold or form which is not constructed in sections, and in which the soffit constitutes an integral part of the mold or form;

Fig. 5 is a bottom view of the mold or 95 form and illustrates the manner of using the wedges to interlock the soffit to the forms;

Fig. 6 illustrates a side elevation of the 100 casting used for interconnecting the tension member to the truss; and,

Fig. 7 is a bottom plan view of said casting.

As illustrated in Fig. 1, the floor and joist 105 mold or form construction is supported on the girder forms 11 and on the stringers 66. The girder form 11 is supported on the cross piece 12 of the T shore 12' which also carries the wedges 13 which supports the stringers 66 which in turn carry the molds or forms 110

- used for the joist and floor construction. The mold or form for the joist or floor construction is clearly illustrated in Figs. 1, 2 and 3, and consists of a U-shaped section 5 14 fitted with the sides 15 and 16 and the top 17. Secured to the sides 15 and 16 of the form 14 are the cleats 17' and 18 respectively, which cleats are utilized to receive the soffits 19. These soffits 19 are preferably continuous for the entire length of the section between the columns and are loosely laid in position on the cleats 17' and 18, after the forms have been placed in position.
- 10 15 The forms 14 are constructed in transverse sections and for use of spans from 16 feet to 18 feet, with moderate loading, the sections can be supported without the use of the truss which is described hereinafter.
- 20 20 If the spans are of greater length than 16 or 18 feet, and the loading is exceptionally heavy, then the truss construction to be described hereinafter is preferably used to hold up the sections and the floor construction thereon. If desired, more than two transverse sections, as described in my pending application No. 331,862, can be used.
- 25 30 The sections 14 are preferably made in the factory or on the bench to accurate length. In the case of a two sectional form, as illustrated in Fig. 1, the splice at the middle of the span is cut at such an angle that one of the end sections can be pivoted around the point of support and can thus be drawn from the other section in stripping. The sides of the sections 14 are braced transversely by nailing a spreader 20 into each section before the sections are erected.
- 35 40 These spreaders function to keep the sections in shape during the process of handling and erecting. When the false work construction is to be wrecked, the first operation is to knock out these spreaders 20.
- 45 50 When two transverse sections are used, as illustrated in Fig. 1, a splice is made at the middle of the span to strengthen the complete structure, the splice being made at the middle of the span because the shearing stresses in the structure at this point are zero. This splice is clearly illustrated in Fig. 1 and comprises the use of two spreaders 21 and 22, which ride against the inner edges of the cleats 23 and 24, respectively, secured to the end of the two sections. The spreaders 21 and 22 are then interconnected and interlocked by any suitable means, preferably by bolts, such as 25, which are threaded through suitable holes in the spreaders 21 and 22 and secured in position to tightly interlock the two sections of the structure by means of the nuts such as 26.
- 55 60 The soffits 19, as hereinbefore described, are loosely placed in position after the sections 14 have been properly positioned.

The soffit 19 is a continuous piece cut to the proper length, and is dropped into position on the cleats 17' and 18. The soffit 19 is interlocked to the sides of the sections 14 by means of a wedge construction illustrated in Figs. 4 and 5. As there illustrated, the soffit 19 carries a cleat 27, which cleat 27 is preferably nailed to the bottom of the soffit. The cleat 27 is fitted at one edge with a second cleat 28, which second cleat 75 28 is preferably nailed to the cleat 27. The cleat 27 is positioned on the soffit so that it is disposed adjacent notches, such as 29, cut in the sides of the forms 14. The notches 29 are cut in the sides of the forms to receive the wedges 30 and 31 which function together with the notches cut in the side and the cleats nailed to the bottom of the soffit 19 to interlock the soffits with the sections or forms 14, so that the entire structure becomes one solid interlocked entity. These wedges 30 and 31 are driven into position after the forms 14 have been placed in position and the soffits 19 laid on the cleats 17' and 18, said wedges serving to force 80 85 the soffits into position and tightly interlock them with the sides 15 and 16. The wedges are driven into position from the side, and, as clearly illustrated in Figs. 4 and 5, bind the soffits to the forms because of the spreading action of the wedges, which spreading action is resisted by the sides of the notches 29 and the cleat 27 nailed to the bottom of the soffit 19. The cleat 28 which is secured to the bottom of the cleat 27 serves as a 90 95 100 guiding and supporting means for the wedges 30 and 31, when they are driven into position to interlock the soffits to the forms 14.

The center splice, hereinbefore described, and with the interlocked soffits, function to utilize the strength of the lumber within the construction of the form to support the form and the floor which is laid thereon. With this center splice and this interlocking wedge construction, the forms or sections, when thus interlocked, will carry substantially the same load which they would carry if the entire falsework were permanently 110 115 interconnected by securely nailing the parts of the falsework together. If the spans are not of a greater length than 18 feet and the loading is moderate, due to this interlocking construction, the forms will ordinarily be strong enough to carry themselves 120 and the floor laid thereon without any additional supporting means. In the longer spans in which the resisting moment of the form itself is insufficient to carry the required load, the truss construction, illustrated in Figs. 1 and 3, is utilized.

This truss construction 38 comprises the two light A-shaped struts 32 and 33 which are preferably placed about 6 feet apart in a longitudinal direction, these A-shaped 125 130

struts being interconnected by the two diagonal struts 34 and 35, which, in turn, are fastened to the top member of the truss 36 and the bottom member 37. These A-shaped struts, together with the interconnecting struts 34 and 35 and the top and bottom members 36 and 37, are made standard for all ordinary lengths of span.

The truss construction 38 is connected to the ends of the standard sections 14 by means of rods or cables such as 40 and 41, which are equipped with eyebolts at either end. The eyebolt 42 at the upper end is threaded through a horizontal piece such as 43, which is securely fastened to the ends of the U-shaped section 14 by end nailing and saddle-cleats 45. The rod or cable connection to the end of the form, by means of the horizontal piece 43 which rides in the saddle-cleats 45, is made before erection and is not disturbed in wrecking or in the re-use of the form. The lower connection of the rod or cable 40 and 41 to the horizontal tension member 37 of the truss is effected by passing the eyebolt through a slot in a casting 47 securely fastened to the horizontal truss member 37.

This casting 47 is illustrated in detail in Figs. 6 and 7. The casting comprises the flat portion 48 fitted with the upturned lug 49, which lug 49 is fitted into a notch 50 in the horizontal truss member 37, the flat portion 48 being preferably secured to the truss member 37 by screws which pass through perforations such as 51. The forward end of the flat portion 48 is fitted with the shoulder 52 which rides over the end of the horizontal truss member 37.

Depending from the horizontal piece 48 are the lugs or radial webs 53 and 54 which form the slot 55 into which the lower eyebolt 56 which secures the cables 40 and 41 to the truss member 37 is fitted. The lugs or radial webs 53 and 54 are provided with an arcuate surface 57, as clearly illustrated in Fig. 6. The eyebolt 56 which is fitted into the slot 55 is equipped with a radial washer 58 having an arcuate upper surface corresponding to that of the surface 57 with which the radial webs are fitted. This radial washer is held on the bolt 56 by any suitable means, preferably by a nut such as 59. The eyebolt 56 is made of sufficient length so that the radial washer will pass over the radial lugs on the casting 47 when the nut is loosened in the wrecking operation. The threads on the end of the bolt 56 are preferably marred so as to prevent the ready removal of the nut 59, and thereby prevent the removal of the radial washer from the bolt 56.

When the bolt 56 is in position between radial webs 53 and 54 and the nut 59 tightened, the radial washer 58 will ride on the radial webs 53 and 54 of the casting 47

and will, therefore, adjust themselves to any angle of the diagonal tension rods or cables 40 and 41, thus forming a perfect bearing between the radial washer 58 and the lugs or radial webs 53 and 54.

70

The truss construction just described is used for the purpose of supporting any load in excess of that which the form itself is capable of supporting or to add sufficient strength to the form construction to eliminate any deflection when long spans are used.

75

Referring now particularly to Fig. 2, it will be noted that each section is equipped with a horizontal wire 60 and a vertical wire 61, these wires being placed in the sections 14 at suitable intervals along the entire length of said section. These wires are used in wrecking for the purpose of breaking the suction between the sides of the concrete of the finished floor and the face of the form, thereby eliminating the necessity of marring the fresh concrete with a pinch-bar, which is the ordinary method used for separating the form from the concrete. In the preferred form of construction using the wire, as illustrated in Fig. 2, the pinch-bar is inserted in the loop of the vertical wire 61 above the horizontal wire. Pressure is then applied to the end of the pinch-bar and because of the insertion of the pinch-bar in the loop above the horizontal wire, the downward pressure on the pinch-bar will be first taken up by the horizontal wire which will warp the sides of the form sufficiently to break the suction between the sides 15 and 16 of the form and the concrete construction. Upon continued application of the downward pressure on the pinch-bar, the strain will next be taken up by the vertical wire, as indicated in the broken line illustrated in Fig. 2, and this will break the suction between the top 17 and the concrete construction. The vertical wire 61 is provided with sufficient slack, as indicated at 63, in order to obtain this interaction between the horizontal wire 60 and the vertical wire 61. After the suction is broken between the top 17 of the section 14, by means of the wire 61, as just described, the form 14 can be readily withdrawn from its position by means of a pivoted motion about the end of the form supported on the column and girder forms.

80

In erecting the forms, it is obviously first necessary to erect in the usual manner the column forms 10 and a portion of the girder forms 11, if the girder forms project below the bottom of the joist. In the event that the girder-forms do not project below the bottom of the joist, then the end piece 64 of the form 14 constitutes a portion of the girder-forms. It is also necessary, as indicated, to first put in place T-shores 12' between the columns on the center lines of the

90

which will warp the sides of the form sufficiently to break the suction between the sides 15 and 16 of the form and the concrete construction. Upon continued application of the downward pressure on the pinch-bar, the strain will next be taken up by the vertical wire, as indicated in the broken line illustrated in Fig. 2, and this will break the suction between the top 17 and the concrete construction. The vertical wire 61 is provided with sufficient slack, as indicated at 63, in order to obtain this interaction between the horizontal wire 60 and the vertical wire 61. After the suction is broken between the top 17 of the section 14, by means of the wire 61, as just described, the form 14 can be readily withdrawn from its position by means of a pivoted motion about the end of the form supported on the column and girder forms.

95

In erecting the forms, it is obviously first necessary to erect in the usual manner the column forms 10 and a portion of the girder forms 11, if the girder forms project below the bottom of the joist. In the event that the girder-forms do not project below the bottom of the joist, then the end piece 64 of the form 14 constitutes a portion of the girder-forms. It is also necessary, as indicated, to first put in place T-shores 12' between the columns on the center lines of the

100

which will warp the sides of the form sufficiently to break the suction between the sides 15 and 16 of the form and the concrete construction. Upon continued application of the downward pressure on the pinch-bar, the strain will next be taken up by the vertical wire, as indicated in the broken line illustrated in Fig. 2, and this will break the suction between the top 17 and the concrete construction. The vertical wire 61 is provided with sufficient slack, as indicated at 63, in order to obtain this interaction between the horizontal wire 60 and the vertical wire 61. After the suction is broken between the top 17 of the section 14, by means of the wire 61, as just described, the form 14 can be readily withdrawn from its position by means of a pivoted motion about the end of the form supported on the column and girder forms.

105

In erecting the forms, it is obviously first necessary to erect in the usual manner the column forms 10 and a portion of the girder forms 11, if the girder forms project below the bottom of the joist. In the event that the girder-forms do not project below the bottom of the joist, then the end piece 64 of the form 14 constitutes a portion of the girder-forms. It is also necessary, as indicated, to first put in place T-shores 12' between the columns on the center lines of the

110

which will warp the sides of the form sufficiently to break the suction between the sides 15 and 16 of the form and the concrete construction. Upon continued application of the downward pressure on the pinch-bar, the strain will next be taken up by the vertical wire, as indicated in the broken line illustrated in Fig. 2, and this will break the suction between the top 17 and the concrete construction. The vertical wire 61 is provided with sufficient slack, as indicated at 63, in order to obtain this interaction between the horizontal wire 60 and the vertical wire 61. After the suction is broken between the top 17 of the section 14, by means of the wire 61, as just described, the form 14 can be readily withdrawn from its position by means of a pivoted motion about the end of the form supported on the column and girder forms.

115

In erecting the forms, it is obviously first necessary to erect in the usual manner the column forms 10 and a portion of the girder forms 11, if the girder forms project below the bottom of the joist. In the event that the girder-forms do not project below the bottom of the joist, then the end piece 64 of the form 14 constitutes a portion of the girder-forms. It is also necessary, as indicated, to first put in place T-shores 12' between the columns on the center lines of the

120

which will warp the sides of the form sufficiently to break the suction between the sides 15 and 16 of the form and the concrete construction. Upon continued application of the downward pressure on the pinch-bar, the strain will next be taken up by the vertical wire, as indicated in the broken line illustrated in Fig. 2, and this will break the suction between the top 17 and the concrete construction. The vertical wire 61 is provided with sufficient slack, as indicated at 63, in order to obtain this interaction between the horizontal wire 60 and the vertical wire 61. After the suction is broken between the top 17 of the section 14, by means of the wire 61, as just described, the form 14 can be readily withdrawn from its position by means of a pivoted motion about the end of the form supported on the column and girder forms.

125

In erecting the forms, it is obviously first necessary to erect in the usual manner the column forms 10 and a portion of the girder forms 11, if the girder forms project below the bottom of the joist. In the event that the girder-forms do not project below the bottom of the joist, then the end piece 64 of the form 14 constitutes a portion of the girder-forms. It is also necessary, as indicated, to first put in place T-shores 12' between the columns on the center lines of the

130

girder and the support 66 for the end bearing of the joist form 14. This support 66 is carried on the ends of the T-shores on wedges 13 to allow for alignment, as hereinbefore described.

A suitable support such as 67 is then placed on temporary supports at the center of the span and at the proper height to receive the sections 14. The sections 14 are 10 then set in place supported on the center support 67 at the middle of the span, and at the other end the sections 14 are supported on the bearing 66, as hereinbefore described.

15 The next operation in the construction of the falsework is to make the center splice connection by inserting the two spreaders 21 and 22 and interconnecting these spreaders by means of the bolts 25 as hereinbefore described. The soffits 19 are next laid in position from the top, after which the interlocking wedges interconnecting the soffits to the forms 14 are driven into place.

In applying the trusses 38 in position the 25 frame portion of the truss is held up in position by a man standing on the floor, while another man slips the eyebolts 56 attached to the cable 40 and 41 into the slots 55 in the castings, as hereinbefore described.

30 The trusses are then drawn up into position by means of the nuts 59, thereby interlocking the truss construction to the joist and floor forms or sections 14. A continuous board 68 is inserted under the sections 14

35 at both end struts of the truss and there tacked in place. This continuous board 68 takes a firm bearing on the cleats 69 which are permanently nailed to the diagonal braces of each A-shaped strut. The continuous board 68 serves to take out any lateral deflection caused by unequal loading or impact in connection with the pouring and the wheeling of the concrete during the time that the floor is being laid. It also assists in 40 supporting intermediate sections.

45 After the sections have been put in place and the truss member positioned as illustrated in Fig. 1, the floor can be poured.

It will be noted that with the construction as shown, the weight of the floor construction is transferred to the center line of the girder, thereby eliminating the use of intermediate T-shores for supporting the floor, which is being constructed upon the floor immediately below.

With the improved construction, as herein shown, therefore, the forms 14 for the floor construction between the center line of the girders can be removed and re-used as 60 soon as the fresh concrete has become strong enough to carry its own weight. Ordinarily the forms or sections 14 may be removed the day after the pouring of the floor by inserting a few temporary shores under the soffit 65 19 near the center of the span, leaving the

soffits in position and withdrawing the sections 14 for other use.

In wrecking the construction, the truss member 38 is best removed by lowering the nuts 59 so that the bolts 56 with the attached 70 washer 58 and nut 59 can be slipped out and over the radial webs 53 and 54, thereby permitting the trusses 38 to be removed from the construction. Following this, the center splice is removed by loosening the 75 nuts 36, after which the suction between the molds or forms 14 and the concrete construction is broken by means of the wires 60 and 61 as hereinbefore described. When the suction is thus broken the forms 14 can 80 be readily rotated out of position about the end bearing on the girder form.

The forms for the falsework construction built in accordance with the teachings of this invention are very advantageous in that 85 they can be constructed to size in the shop or factory where this construction can be cheaply accomplished and the forms more accurately made. The forms being independent of the soffits and the soffits being 90 positively interlocked to the forms, after they have been placed in position, by means of the wedge construction described, gives a falsework made of standardized parts 95 which can be readily adapted to any size construction and which is as solid and substantial as a form made on the job of solid construction throughout. The standardization of the parts of the form with the interlocking means, whereby the material from 100 which the form is made is utilized, not only to act as a form for shaping the concrete but also to add strength to the construction, is a decided advantage, especially when these 105 results are obtained in a construction made of a plurality of parts which can be readily and cheaply and efficiently constructed at the shop or mill. By constructing these 110 standardized parts at the shop or mill, a great saving is effected. The construction 115 of these parts on the job where the concrete pouring is to be done is always very expensive and exceedingly inefficient. This 120 standardized construction, in which a plurality of parts are used, rather than interconnecting and nailing the form into a one piece construction, results in decided advantages in wrecking, inasmuch as the parts are not damaged in this operation and can be reused enumerable times, thus materially decreasing the cost of concrete falsework construction.

Obviously the invention is not limited to the specific form thereof herein illustrated and described, but is capable of other applications and many variations within the spirit and scope of the invention as pointed out in the following claims.

What I claim as new and desire to secure by Letters Patent of the United States is:

1. A form for concrete construction comprising, in combination, a top and two sides, and means interconnecting said top and sides adapted to break the suction, first, between the sides of said form and the concrete and, next, between the top of said form and the concrete.

2. A form for concrete construction comprising, in combination, a top and two sides, a wire interconnecting said sides, a second wire connected to said top and means interconnecting said first and second wires adapted to break the suction, first, between the sides of said form and the concrete and, next, between the top of said form and the concrete.

3. A form for concrete construction comprising, in combination, a top and two sides, a wire interconnecting said sides, a second wire connected to said top, and a loop at the end of said second wire which encircles said first wire, said wires being adapted to cooperate to break the suction, first, between the sides of said form and the concrete and, next, between the top of said form and the concrete.

4. A built-up structure for concrete construction comprising, in combination, a plurality of forms, each having a top and two sides, soffit supporting means secured to the sides of said forms, a soffit loosely laid in place between said sides and said means, a cleat secured to said soffit, a second cleat secured to said first cleat, notches in the sides of said forms and wedges cooperating with said notches, said sides and said cleats to rigidly secure said soffit to said sides to interlock and strengthen said structure.

5. A built-up structure for concrete construction comprising, in combination, a plurality of transverse forms, cleats secured to the ends of said forms, spreaders adapted to be positioned against the inner edge of said cleats, and means for interlocking

said spreaders to rigidly interconnect and 45 interlock said transverse sections.

6. A built-up structure for concrete construction comprising, in combination, a plurality of transverse sections, means provided at the middle of said span for interconnecting said sections, a truss construction adapted to assist in supporting said structure, cables for interconnecting said truss construction to said forms at the outer ends of the span, and means interconnecting said 50 cables with said truss construction, whereby the interconnection between the cable and the truss construction will be self-adjusting for any angle which the cable assumes.

7. A built-up structure for concrete construction comprising, in combination, a plurality of transverse sections, means for interconnecting said sections at substantially the middle of the span, a truss member, a saddle cleat secured to said forms at the ends 60 adjacent the ends of the span, a straddle member secured in said saddle cleats, and means interconnecting said saddle member and said truss member to interconnect said truss member with the ends of said forms. 65

8. A built-up structure for concrete construction comprising, in combination, a plurality of transverse sections, means for interconnecting said sections at substantially the middle of the span, a truss member, a 75 saddle cleat secured to said forms at the ends adjacent the ends of the span, a straddle member secured in said saddle cleats, means interconnecting said saddle member and said truss member to interconnect said truss member with the ends of said forms, and means for placing said last mentioned means under tension whereby said truss member will act as a support for said structure.

In witness whereof, I have hereunto subscribed my name.

JOHN A. TAGGART.
